[57] CLAIM

The ornamental design for a game cabinet, as shown and described.

DESCRIPTION

FIG. 1 is a perspective view of a game cabinet embodying my new design.

FIG. 2 is a top plan view of the game cabinet shown in FIG. 1.

FIG. 3 is a front elevational view of the game cabinet shown in FIG. 1.

FIG. 4 is an elevational view of the right hand side of the game cabinet shown in FIG. 1.

The back and bottom of the game cabinet are generally planar surfaces, and the left side is a mirror image of the right side.
